UNITED STATES PATENT OFFICE.

EBEN R. PACKER, OF WILMETTE, ILLINOIS, ASSIGNOR TO Q & C COMPANY, OF NEW YORK, N. Y., A CORPORATION OF MAINE.

ADJUSTABLE DERAILING DEVICE.

1,242,847.

Specification of Letters Patent.

Patented Oct. 9, 1917.

Application filed March 8, 1916. Serial No. 82,783.

To all whom it may concern:

Be it known that I, EBEN R. PACKER, a citizen of the United States, residing at Wilmette, county of Cook, State of Illinois, have 5 invented a certain new and useful Improvement in Adjustable Derailing Devices, and declare the following to be a full, clear, and exact description of the same, such as will enable others skilled in the art to which it 10 pertains to make and use the same, reference being had to the accompanying drawings, which form a part of this specification.

My invention has for one of its objects to produce a simple derailing device adjustable to rails of various sizes.

In my prior Patent No. 1,167,924 issued January 11, 1916 I have illustrated a derailing device in which the hinge connection between the block and its support is radially 20 adjustable and, in my present device, I make use of this same radial adjustment but vary the structural details so as to make the device simpler and stronger.

A second object of my invention is to produce a strong, light, rigid support or standard on which may be mounted a hinged or swinging derailing block.

The various features of novelty whereby my invention is characterized will herein- 30 after be pointed out with particularity in the claims; but, for a full understanding of my invention and of its objects and advantages, reference may be had to the following detailed description taken in connection with 35 the accompanying drawings, wherein:

Figure 1 is a side view of a derailing device embodying both features of my invention looking to the side which is next to the rail, and portions being broken away to expose other portions;

Fig. 2 is a top plan view;

Fig. 3 is an end view of the device illustrated in Fig. 1, a railway rail being illustrated in conjunction with the device;

Fig. 4 is a top plan view of a slightly modified form of device in co-operative relation to a rail; and

Figs. 5 and 6 are respectively a top plan view and an end elevation of a still further modified form in operative relation to a rail.

Referring first to Figs. 1 to 3 of the drawings, 1 represents a flat plate adapted to rest at its ends upon two railway ties and be 55 held against displacement in the direction

of the length of the rails not only by suitable fastening devices but also by means of a downwardly projecting shoulder which may conveniently take the form of a frame-like rib or flange adapted to fit between and abut against two adjacent ties. At the inner edge of the plate are upwardly and inwardly projecting extensions, 3, adapted to fit against the web of a rail, 4. Projecting upwardly from the top of the plate are separated posts or standards, 5, which may conveniently be strengthened and reinforced by suitable webs, 6, extending inwardly and connected with the members 3. The plate preferably has the middle portion removed 65 so that it itself is in the form of a frame-like structure surrounding a large central opening, 7. This arrangement permits great 70 strength to be combined with lightness.

Between the standards, 5, is hinged a derailing block, 8, of any suitable construction. The block illustrated in the figures under discussion is a common form of block operative to derail a wheel traveling in one direction only. The block is provided with arms, 9, projecting outwardly from the bottom thereof and spaced apart so as to be a comfortable working fit between the two standards. The arms are stiffened and braced by means of a web, 10, extending from the top of one to the top of the other. A bolt, 11, passing through the standards and the arms serves to hold the block pivotally on the stationary support. In order to make the device adjustable to rails of different 85 heights, I make the openings in the standards through which the bolt passes in the form of vertically elongated slots, 12; provide the outer faces of the standards with transverse teeth, 13; and arrange between 90 the head, 14, and the nut, 15, of the bolt washers, 16, having teeth, 17, adapted to mesh with the teeth on the standards. When the two washers are brought properly into mesh with the teeth on the standards and the nut on the bolt is tightened, the bolt is rigidly clamped against vertical displacement. The adjustment of rails to different 95 heights is therefore secured by simply loosening the nut, shifting the washers up or down and then again tightening the nut.

One of the arms, 9, is provided with an outwardly projecting perforated boss, 18, by means of which the swinging block may be attached to a target stand connection. The 110

other arm, 9, is provided with a perforated lug, 19, so disposed that when the block is resting upon the rail, in derailing position, the shackle of a padlock may be passed 5 through the lug, 19, and serve as a stop co-operating with the adjacent standard to prevent the block from being swung out of its derailing position.

In order to take the twisting stresses off 10 the teeth between the standards and the washers, I provide in the outer face of each standard a vertical keyway, 20, into which projects a lug or key, 21, formed on the inner side of the corresponding washer. 15 These keyways and keys prevent the washers from turning and therefore insure that the teeth will always be properly in mesh and will not tend to cross each other.

The arrangement illustrated in Fig. 4 is 20 the same as that heretofore described except that the derailing block, 25, is made double ended so that it will derail a wheel going in either direction. Thus there are rising inclines, 26, at opposite ends and two deflecting or derailing flanges, 27, for engaging with the side of the wheel flange and pressing the wheel over.

In the arrangement illustrated in Figs. 5 and 6 the construction is the same in substance as that heretofore described except that the base plate, 30, is made somewhat larger, and from the web, 31, which connects the two supporting arms, 9, of the derailing block extend three ears, 33, to which 35 are connected posts, 34, extending down through the opening, 35, in the base plate and connected at points beneath the base plate with actuating rods, 36. The posts may be rigidly connected to the actuating 40 rods and be hinged to the ears 33; the hinge connection being conveniently effected by inserting a single bolt, 37, through the three ears and overlapping portions or jaws of the post, 34. This arrangement provides for 45 operating, for bolt lock and for facing point lock.

I claim:

1. In combination, a derailing block, a stationary support, said block and said support having members lying side by side, said members having registering openings one of which is in the form of an elongated slot, a bolt passing through said slot and through an opening in the other member, the slotted 55 member having teeth extending transversely of the slot in its exposed face, a washer on said bolt having teeth adapted to mesh with

the aforesaid teeth, and means for interlocking the washer and the co-operating toothed member independently of the teeth so as to hold the washer positively against rotation. 60

2. In combination, a derailing block, a stationary support, said block and said support having members lying side by side, said members having registering openings one of which is in the form of an elongated slot, a bolt passing through said slot and through an opening in the other member, the slotted member having teeth extending transversely of the slot in its exposed face, a washer on 70 said bolt having teeth adapted to mesh with the aforesaid teeth, and interlocking shoulders between the washer and the co-operating toothed member extending transversely of the teeth to prevent rotation of the washer. 75

3. In combination, a derailing block, a support, said support having therein a slot elongated in the vertical direction, said block having a member engaging with one side of the support, a bolt passing through said support, the face of said support on the side opposite to that on which said member lies having teeth extending transversely of the slot, and a washer on the bolt having teeth meshing with the aforesaid teeth. 85

4. In combination, a derailing block, a support, said support having therein a slot elongated in the vertical direction, said block having a member engaging with one side 90 of the support, a bolt passing through said member and through the slot in said support, the face of said support on the side opposite to that on which said member lies having teeth extending transversely of the slot, a washer on the bolt having teeth meshing with the aforesaid teeth, and interlocking shoulders between said support and said washer for holding the washer against rotation independently of the teeth. 100

5. In combination, a support comprising a flat frame-like base plate having standards projecting upwardly from opposite ends thereof, a derailing block having arms lying between and in proximity to said standards, a bolt device passing through said standards and said arms to form a hinge connection for the block, and actuating means for the block extending from the latter down through the opening in the base plate. 105

In testimony whereof, I sign this specification.

EBEN R. PACKER.
